EXPANDING FLAME OIL BURNER SYSTEM

Lester D. Cotea, Dayton, Minn., assignor to Minneapolis-Honeywell Regulator Company, Minneapolis, Minn., a corporation of Delaware

Application April 28, 1934, Serial No. 722,907

1 Claim. (Cl. 158—28)

The present invention relates to improvements in fuel burning systems and is particularly concerned with the provision of a fuel burning system in which the supply of fuel is increased after combustion has been properly established.

The object of the present invention is the provision of a fuel burning system including valve mechanism adapted to supply either a large or a small amount of fuel to a burner, and to entirely interrupt the supply of fuel thereto, together with means for initially operating the valve mechanism in such manner as to cause the same to supply a small amount of fuel to the burner which, if successfully ignited, is thereafter increased to a larger supply. In this manner, a trial ignition period can be instituted without delivering a large amount of fuel to the burner and if this ignition period is successful in establishing combustion, then the full desired supply of fuel is established thereby making it possible to check the operation of the system without delivering a very large supply of fuel to the burner in the event ignition is not successful.

The invention further includes the usual safety mechanism by which the system is rendered inoperative in case combustion is not successfully established and the arrangement is such that the large supply of fuel cannot be furnished to the burner before the safety mechanism has checked the operation of the apparatus.

In the specific embodiment of the invention herein disclosed, the valve mechanism comprises a pair of valves one of which is preferably a low capacity valve and the other of which is preferably a high capacity valve. The low capacity valve is initially energized under the command of a main control device and, in the event the supply of fuel furnished by this low capacity valve is successfully ignited, then the high capacity valve is energized and the low capacity valve is deenergized. The ignition means for igniting the fuel supply to the burner is controlled simultaneously with the low capacity valve in the preferred form of the invention. Also, it is preferable to provide a burner motor which is energized the whole time that the system is in operation.

The system also is preferably arranged to give a recycle upon a failure of flame or momentary power failure.

Other objects of the invention will be found in the drawing, the following description and in the appended claim.

For a better understanding of the invention, reference may be had to the following detailed

description and the accompanying single drawing which is a diagrammatic showing of one form of the present invention.

Referring to the drawing, the valve mechanism comprises a low capacity valve 10 which is operated by an electromagnetic winding 11 and a high capacity valve 12 which is operated by an electromagnetic winding 13, the arrangement being such that valves 10 and 12 are moved to open position upon energization of their respective electromagnetic windings 11 and 13. The fuel supplied by the low capacity valve 10 is ignited by an electrically operated ignition means 14. Preferably, the system includes a burner motor 15 which serves to supply the combustion supporting air and atomizes or mixes the fuel and air in any of the manners now well-known in the art.

The system is controlled by a main control indicated generally at 16 which is herein shown as comprising a room thermostat which includes a bimetallic coiled element 17 having one of its ends fixed as indicated at 18. The other end of bimetallic element 17 controls a contact blade 19 and a contact blade 20. When the room temperature falls, contact blade 19 first engages a contact 21 and upon further fall in the room temperature contact blade 20 engages a contact 22. Similarly, upon a room temperature rise, the contact blade 20 first disengages its contact 22 and thereafter the contact blade 19 disengages its contact 21.

The system further includes a thermal safety switch which comprises a switch 25 that is thermally operated and an electric heating element 26 for operating the same. Such thermally operable switches are well-known in the art and the thermal safety switch utilized in the present invention may well take the form shown in Frederick S. Denison application Ser. No. 226,395 which was filed October 15th, 1927.

The system of the present invention further includes a combustion responsive switching mechanism which preferably takes the form of a slip friction stack switch generally indicated at 28. The stack switch 28 includes first cold and hot switches comprising contacts 29 and 30 and a switch arm 31 that is operated through suitable slip friction mechanism, the arrangement being such that switch arm 31 engages contact 29 in the absence of combustion and engages contact 30 upon the establishment of combustion. The arrangement is such that switch arm 31 engages contact 30 prior to disengaging contact 29 upon establishment of combustion but does not en-

gage contact 29 until a delayed interval after disengaging contact 30 upon cessation of combustion. The stack switch 28 further includes second cold and hot switches comprised by a mercury switch 32 having a pair of cold electrodes 33 and a pair of hot electrodes 34 adapted to be bridged by a body of mercury 27. Stack switch mechanisms of this general character are well-known in the art and the one diagrammatically illustrated herein may well take the general form shown in Figs. 2 and 3 of Frederick S. Denison application Ser. No. 697,687, filed November 11th, 1933.

The room thermostat 17 and the stack switch 28 cooperate in the control of a relay 35 which comprises a relay coil 36 that attracts an armature 37 when energized. An armature 37 controls switch arms 38, 39 and 40 to move the same into engagement with respective contacts 41, 42 and 43 upon energization of relay coil 36.

High voltage electrical power is furnished to the system by line wires 45 and 46. Low voltage electrical power is furnished by a step-down transformer 47 having a low voltage secondary 48 and a high voltage primary 49 which is connected to line wires 45 and 46 by wires 50 and 51.

The remaining circuit connections will be described under the heading "Operation".

Operation

With the parts in the position shown, the room temperature is above the desired value and the relay coil 36 is deenergized. The cold switches comprising switch arm 31 and contact 29 and the electrodes 33 of mercury switch 32 are both closed and the combustion responsive hot switches comprised by arm 31 and contact 30 and the electrodes 34 of mercury switch 32 are both opened indicating that there has been a decrease in the temperature of combustion. Low and high capacity valves 10 and 12 are both closed and the ignition means 14 and burner motor 15 are both deenergized.

When the room temperature drops so as to bring contact blades 19 and 20 sequentially into engagement with their contacts 21 and 22, an energizing circuit for the relay coil 36 and heating element 26 is established as follows: secondary 48, wire 55, safety switch 25, wire 56, contact 21, contact blades 19 and 20, contact 22, wire 57, wire 58, switch arm 31, cold contact 29, wire 59, heating element 26, wire 60, wire 61, relay coil 36 and wire 62 to the other side of secondary 48. Energization of relay coil 36 moves switch arms 38, 39 and 40 into engagement with their respective contacts 41, 42 and 43. Engagement of switch arm 39 with its contact 42 establishes a holding circuit for relay coil 36 and heating element 26 as follows: secondary 48, wire 55, safety switch 25, wire 56, contact 21, contact blade 19, bimetallic element 17, wire 63, contact 42, switch arm 39, wire 64, wire 58, switch arm 31, contact 29, wire 59, heating element 26, wire 60, wire 61, relay coil 36 and wire 62 to the other side of secondary 48.

Engagement of switch arm 40 with contact 43 establishes energizing circuits for burner motor 15, ignition means 14 and low capacity valve 10. The energizing circuit for burner motor 15 is as follows: line 45, wire 65, contact 43, switch arm 40, wire 66, wire 67, burner motor 15, and wire 68 to line 46. The energizing circuits for ignition means 14 and low capacity valve 10 are as follows: line 45, wire 65, contact 43, switch arm 40, wire 66, wire 69, wire 70,

cold electrodes 33 and the bridging mercury 27 of mercury switch 32 and wire 71 at which point the circuit branches, one part going by way of wire 72, ignition means 14 and wire 73 to line 46, whereas the other portion goes by way of 5 wire 74, electromagnetic winding 11 of low capacity valve 10, wire 75, and wire 76 to line 46.

In this manner, upon a call for heat by the room thermostat 16, the burner motor 15 is energized and a small supply of fuel is furnished to the burner which should be ignited by the ignition means 14. In the event ignition is not successfully established within a predetermined timed period, the heating element 26 will cause opening of safety switch 25 whereupon the system 15 will be rendered inoperative until manual intervention. On the other hand, if combustion is successfully established within this period, switch arm 31 will move into engagement with contact 30 and thereafter will disengage contact 29. 20 Likewise, mercury switch 32 will tilt to its opposite position wherein the hot electrodes 34 are bridged by the mercury 27 thereof.

Engagement of switch arm 31 with contact 30 immediately establishes a maintaining circuit for 25 relay coil 36 which maintaining circuit operatively deenergizes heating element 26 by establishing a shunt therearound. This maintaining circuit is as follows: secondary 48, wire 55, safety 30 switch 25, wire 56, contact 21, contact blade 19, bimetallic element 17, wire 63, contact 42, switch arm 39, wire 64, wire 58, switch arm 31, contact 30, wire 79, switch arm 38, contact 41, wire 80, wire 61, relay coil 36 and wire 62 to the other side of secondary 48. Then as soon as 35 switch arm 31 disengages contact 29, the original energizing and holding circuits for relay coil 36 and heating element 26 are interrupted. Movement of mercury switch 32 to its hot position 40 opens the circuit between cold electrodes 33 to interrupt the energizing circuits for ignition means 14 and low capacity valve 10. Closure of the circuit through hot electrodes 34 of mercury switch 32 however establishes an energizing 45 circuit for high capacity valve 12 which is as follows: line 45, wire 65, contact 43, switch arm 40, wire 66, wire 69, wire 80, hot electrodes 34 and the mercury 27 of mercury switch 32, wire 63, electromagnetic winding 13 of high capacity valve 12, wire 84, and wire 76 to line 46. 50 The system is now in normal operation, combustion having been established and resulting in an increase in the supply of fuel.

When the room temperature begins to rise so 55 as to move contact blade 20 from engagement with contact 22, relay coil 36 will be maintained energized either by the previously described holding circuit or by the maintaining circuit. However, when the room temperature rises sufficiently 60 to additionally move contact blade 19 from engagement with contact 21, then the maintaining circuit will be interrupted, as will be the holding circuit if switch arm 31 has not as yet disengaged contact 29, and the relay coil 36 will be deenergized. This relay coil cannot thereafter be again energized until such time as the room temperature falls sufficiently to bring both contact blades 19 and 20 into engagement with their respective contacts 21 and 22 and until switch 70 arm 31 disengages contact 30 and engages contact 29.

In the event there should be a failure in the supply of electrical power while the system is in operation, relay coil 36 will be deenergized and 75

cannot be again energized upon resumption of power unless the stack temperature has decreased sufficiently to move switch arm 31 from engagement with contact 30 and into engagement with contact 29. Also, at this time, both blades 19 and 20 of the room thermostat 16 must be in engagement with their contacts 21 and 22 in order to reenergize relay coil 36. In the event there should be a failure of flame during normal operation, switch arm 31 will first disengage contact 30 whereupon relay coil 36 will be deenergized after which, upon engagement of switch arm 31 with contact 29 and if the room thermostat switches are both closed, relay coil 36 and heating element 26 will again be energized to establish a new trial ignition period. If combustion is not successfully reestablished at this time the system will be rendered inoperative by the safety switch and remain so until manual intervention.

From the foregoing description, it will be observed that the present invention provides a trial ignition period in which a relatively small amount of fuel is supplied. If ignition is not established, the system is shut down without very much fuel having been delivered to the burner or combustion chamber. In the event combustion is successfully established, the supply of fuel is increased to the desired amount. In this manner, if the system is not operating properly a much smaller amount of fuel is supplied to the burner before the system is rendered inoperative by the safety mechanism.

It will also be noted that the invention provides all of the other usual features such as a recycle upon power failure or flame failure, together with control of the ignition means.

It will be apparent that many changes in the specific arrangement shown herein can be made by those skilled in the art and I therefore intend to be limited only by the scope of the appended claim.

I claim:

In combination, a room thermostat, a thermal safety switch including an electric heating element, a relay coil, a control switch and a load switch closed thereby when energized, first cold and hot combustion responsive switches overlap- 15 pingly controlled upon a rise in the temperature of combustion, an energizing circuit for said relay coil and heating element in series including said room thermostat, safety switch and first cold combustion responsive switch, a holding circuit 20 for said relay coil including said room thermostat, first hot combustion responsive switch, and said control switch, a burner motor, ignition means, a low capacity fuel valve, second hot and cold combustion responsive switches, circuit con- 25 nections controlled by said load switch and sec- 30 ond cold switch for energizing said low capacity valve and said ignition means, an energizing circuit for said burner motor controlled by said load switch, a high capacity fuel valve, and an energizing circuit therefor controlled by said load switch and said second hot switch.

LESTER D. COTEA.
